UNITED STATES PATENT OFFICE.

PHILEMON B. CANFIELD, OF SYRACUSE, NEW YORK.

BORING AND REAMING TOOL.

Application filed February 14, 1921. Serial No. 444,918.

To all whom it may concern:

Be it known that I, PHILEMON B. CANFIELD, a citizen of the United States, residing at Syracuse, in the county of Onondaga and State of New York, have invented certain new and useful Improvements in Boring and Reaming Tools; and I do hereby declare the following to be a full, clear, and exact description of the invention, such as will enable others skilled in the art to which it appertains to make and use the same.

This invention relates to improvements in boring and reaming instruments, and has for its primary object the increase of the facility of operation of such instruments.

A more detail object is the provision of an apparatus capable of use in cylinders while in positions ordinarily considered inaccessible, and a further object is the construction of the instrument in such form as to enable its use to insure the truing up of cylinders to a glass smoothness without limitation as to the size of the cylinder.

A still further object is the provision of a tool of this character capable of operating on a cylinder only for the areas of travel of the piston rings, so that worn sections of used cylinders may be rendered true without varying areas beyond such sections.

With these and further objects in view as will in part hereinafter become apparent and in part be stated, the invention comprises certain novel constructions, combinations and arrangements of parts as subsequently specified and claimed.

In the accompanying drawings,—

Figure 1 is a view in side elevation of an instrument embodying the features of the present invention.

Figure 2 is a bottom plan view thereof, the inner surface of a surrounding cylinder being indicated by the dotted line.

Figure 3 is an enlarged, detail, vertical section through the swivel nut and collar, a fragment of the spindle shaft being shown in elevation.

Referring to the drawings by numerals, 1 indicates a spindle which may be hollow, or otherwise constructed as preferred, and has one end squared, or otherwise appropriately shaped, as indicated at 2, for receiving an operating tool. The end 2 will be hereinafter identified as the "upper" end, since in ordinary or usual operations the said end will

be uppermost, while the other parts will be proportionately lower, it being understood, of course, that inversion or other alteration in the position of the instrument is not to detract from the application of the reference to the said end as "upper" and the opposite end as "lower" as hereinafter mentioned.

At the lower end portion, and also at a point spaced above the lower end portion, the spindle shaft 1 is provided with enlargements 3, 3, each finished to form four flat faces 4, 4, forming the major portion of what, in cross section, would be a perfect rectangle if the lines of the faces were continued to meeting edges. In the construction of the enlargements 3, however, it is unnecessary that enough material be used to so extend the faces 4 whose functions will hereinafter become apparent. A set of links or arms 5, 5, is provided for each enlargement 3, one arm being provided for each face 4, and the inner end of each arm is pivotally connected to the respective enlargement 3 by a retaining tap screw or bolt 6. The head of each bolt 6 is of sufficient size to form a bearing at one face of each arm or link 5, and the respective face 4 forms a bearing at the other face of the link so that the link, while free to swing pivotally on the respective bolt 6, is held against any lateral play. The arm or link 5 of any given face 4 has a corresponding co-operating link 5 engaging the case 4 above or below, as the case may be, and these two links may be referred to as a pair. To the outer ends of each pair of links 5 is connected a cutter bar 7, the connection being pivotal and the pivot being sufficiently snugly fit as to prevent any looseness between the respective cutter bar and its carrying links 5. As shown, each of the said pivots consists simply of a bolt 8 extending through the respective link 5 and threaded through the given cutter bar 7. Any other appropriate form of pivot may obviously be substituted. Thus the cutter bars 7 are rigidly connected to the spindle shaft 1, so far as torsional stress is concerned, but are free to move bodily toward and away from the spindle shaft while maintaining parallelism with respect to each other and with respect to the shaft by movement of the links 5 in the manner indicated by the dotted line position seen

100
95
105

in Figure 1. To effect this movement when desired, and to hold the cutter bars in given positions, to each cutter bar is pivoted a link 9, which extends upwardly and inwardly toward the spindle shaft 1, and at its upper end is pivotally connected to an ear 10 extending from a bracket 11 outstanding from an annulus or swivel plate 12, there being a number of brackets 11 equal to the number of cutter bars 7. The annulus or swivel plate 12 is mounted in an annular groove in the swivel nut 13, which nut is threaded to the threaded section 14 of the spindle shaft 1, the said threaded section 14 being appropriately located for enabling desired collapsing and expanding movements of the cutter bars 7 by the shifting of the nut 13 along the spindle shaft 1. While the manner of introduction of the annulus or swivel plate 12 into the groove of nut 13 has not been indicated on the drawing, it will be readily understood by those skilled in the art that this may be accomplished by the swaging of 25 the material of the lower portion of the nut 13 outward to form the swivel-plate-receiving groove after the plate has been placed in position, or the parts may be otherwise assembled in any well known manner for effecting the swivel connection between plate 12 and nut 13.

It will thus be apparent that by threading the nut 13 upward along spindle shaft 1, the links 9 will be drawn upward and as the cutter bars 7 are correspondingly raised they will be moved outward with a parallel-ruler movement until they stand to the extent required for the particular operation at hand. It is further to be observed that the fact that the cutter bars 7 are carried by links 9 in positions off center with respect to the axis of movement of the instrument causes the cutting edges of cutter bars 7 to contact with the surrounding cylinder walls along a single line, as clearly shown in Figure 2, and all possibility of binding and resultant vibratory or "chattering" action is avoided.

The operation of the instrument will be obvious to those skilled in the art, and consists in inserting the cutter bars 7, adjusting the nut 14 for setting the bars to the desired cutting position, and then rotating the spindle 1 by the application of an appropriate instrument to the squared end 2. It is thus apparent that the instrument is applicable to a great variety of sizes of cylinders, and one instrument may be made to be used with all sizes of popular types of automobile engine cylinders. Furthermore, with this instrument, it is not necessary, when operating on scored or otherwise injured or worn cylinders, to cut away any portion or portions not within the area 60 of the travel of the piston rings. The ca-

pacity of the instrument to collapse and to expand enables it to be applied in the exact location where the operation is to be performed, and when that area representing the full travel of the piston rings has been 70 rendered true and glass smooth, the instrument may be collapsed and withdrawn without further operation. It will also be readily understood that the instrument may be introduced into the cylinder of an engine without removing the cylinder from the car or otherwise from its bed.

It is to be noted that a sufficient tightening of the bolts forming the pivots for the several links 9 would hold the cutter bars in 80 operative position without the aid of the links 9 and their connections, especially where changes in the adjustment were infrequent, but manipulation of the nut 13 and parts actuated thereby enables quick and 85 easy adjustment and assures a fixed and stable relation of the cutter bars in any given adjusted position, and greatly enhance the value of the instrument for ease and accuracy of operation.

What is claimed is:—

1. The combination of a spindle shaft, cutter bars pivotally carried thereby and spaced therefrom, the cutter bars being movable relative to the shaft while maintaining 95 substantial parallelism with respect to the axis of the shaft, and means for retaining the cutter bars at any of various positions with respect to the shaft, the cutter bars being carried in a position off-center with 100 respect to the axis of rotation of the shaft.

2. The combination of a spindle shaft, links pivoted thereto to swing longitudinally thereof off-center with respect to the plane of the axis of the shaft, cutter bars 105 carried by said links and adjustable therewith in planes spaced laterally of the plane of the axis of the shaft and beyond the shaft and its connections, and means for securing the cutter bars in their various positions.

3. The combination of a spindle shaft, links pivoted thereto to swing longitudinally thereof at one side of the plane of the axis of the shaft, cutter bars carried by said links and movable therewith in planes 115 spaced laterally of the plane of the axis of the shaft, a nut threaded on the shaft, and means swivelled to the nut and engaging the cutter bars for retaining the latter in various positions, the cutter bars lying beyond the path of extended lines of the nut.

4. The combination of a spindle shaft, pairs of links pivoted to the shaft and outstanding therefrom beyond the path of extended lines of the shaft and its connections, 125 and a cutter bar pivoted to the outer portions of each pair of links, the cutter bars being adjustable on their links to different positions varying in distance from the shaft.

5. The combination of a spindle shaft, bodily-movable, parallel cutter bars adjacent thereto, and links connecting the cutter bars to the shaft and pivoted to the shaft laterally of the axis of the shaft.
6. The combination of a spindle shaft, cutter bars adjacent thereto, and a pair of links for each cutter bar pivoted to the cutter bar and swiveled to the shaft.
10. 7. The combination of a spindle shaft, cutter bars adjacent thereto, a pair of links for each shaft pivoted to the cutter bar and swiveled to the cutter bar, and means for retaining the cutter bars in various positions.
15. 8. The combination of a spindle shaft, cutter bars adjacent thereto, a pair of links for each cutter bar pivoted to the shaft and to the cutter bar, a nut threaded onto the shaft, and links pivotally engaging the cutter bars and having a swivelled connection with the nut.
20. 9. A reamer comprising a spindle shaft having a plurality of flat faces at the sides of the shaft, links pivoted to the shaft to swing across said faces at the side of the
25. axis of rotation of the shaft, and cutter bars carried by the links.
10. A reamer comprising a spindle shaft having an enlargement provided with flat faces spaced from the axis of rotation of the shaft, a link for each flat face pivoted to the shaft in position for swinging across portions of the respective flat face at one side of said axis, and cutter bars carried by the links.
11. A reamer comprising a spindle shaft having spaced enlargements, each formed with flat faces spaced from the axis of rotation of the shaft, a linkage pivoted to the shaft for each pair of flat faces and comprising a pair of links, each adapted to swing across portions of its respective flat face, and a cutter bar carried by each pair of links off-center with respect to said axis.

In testimony whereof I affix my signature in presence of two witnesses.

PHILEMON B. CANFIELD.
